[57] CLAIM

The ornamental design for a rescue lift, as shown and described.

DESCRIPTION

FIG. 1 is a depiction of the rescue lift of the instant invention in order to display the environment in which the rescue lift may be used.

FIG. 2 is an enlarged front elevation view of the rescue lift of the instant invention.

FIG. 3 is an enlarged rear elevation view of the rescue lift of the instant invention.

FIG. 4 is an enlarged side elevation view of the rescue lift of the instant invention. The opposite side elevation view is the mirror image.

FIG. 5 is an enlarged bottom view of the rescue lift of the instant invention.

FIG. 6 is an enlarged top view of the rescue lift of the instant invention.

The broken line showing of a human figure and rope is for illustrative purposes only and forms no part of the claimed design.
